(57) **CLAIM**

The ornamental design for a pool floater, as shown and described.

DESCRIPTION

FIG. 1 is a front, left, and top perspective view of a pool floater, showing our new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, illustrated in another configuration.
The dash-dot broken lines define the bounds of the claimed design and form no part thereof. The broken lines in the drawings depict portions of the pool floater that form no part of the claimed design.

1 Claim, 9 Drawing Sheets
